Primary Examiner — Ian Simmons*Assistant Examiner* — Richelle G Shelton(74) *Attorney, Agent, or Firm* — Banner & Witcoff, Ltd.(57) **CLAIM**

The ornamental design for a display screen with graphical user interface, as shown and described.

DESCRIPTION

FIG. 1 is a front view of a display screen with graphical user interface showing my new design; and,

FIG. 2 is a front view of a display screen with graphical user interface showing an alternative embodiment of the design of FIG. 1.

The broken line showing of the display screen is for environmental purposes only and forms no part of the claimed design.
